UNITED STATES PATENT OFFICE

120,366

DESIGN FOR A SAFETY LATCH FOR AUTOMOBILE DOORS

Joel R. Thorp, West Allis, Wis., assignor to The
Fulton Company, West Allis, Wis., a corpora-
tion of Wisconsin

Application October 2, 1939, Serial No. 87,464

Term of patent 3½ years

To all whom it may concern:

Be it known that I, Joel R. Thorp, a citizen of the United States, residing at West Allis, in the county of Milwaukee and State of Wisconsin, have invented a new, original, and ornamental Design for a Safety Latch for Automobile Doors, of which the following is a specification, reference being had to the accompanying drawing, forming part thereof.

In the drawing:

Fig. 1 is a perspective view of a safety latch for automobile doors, embodying my new design; and

Fig. 2 is a top view of the safety latch.

I claim:

The ornamental design for a safety latch for automobile doors, substantially as shown.

JOEL R. THORP.
